UNITED STATES PATENT OFFICE.

WILLIAM D. WALKER, OF SACRAMENTO, CALIFORNIA.

DESIGN FOR A CASING FOR DICE-THROWING MACHINE.

Application filed December 14, 1926. Serial No. 20,044. Term of patent 7 years.

To all whom it may concern:

Be it known that I, WILLIAM D. WALKER, a citizen of the United States, residing at Sacramento, in the county of Sacramento and State of California, have invented a new, original, and ornamental Design for a Casing for Dice-Throwing Machine, of which the following is a specification, reference being had to the accompanying draw-

ing, forming part thereof.

The figure is a perspective elevation of a casing for dice throwing machine, showing my new design.

I claim:—

The ornamental design for a casing for dice throwing machine, as shown.

WILLIAM D. WALKER.
